MOTOR CAR TRUCK

Filed Dec. 12, 1928

UNITED STATES PATENT OFFICE

IRWIN A. SEIDERS, OF READING, PENNSYLVANIA, ASSIGNOR TO FLEXIBLE TRUCK CORPORATION, OF PHILADELPHIA, PENNSYLVANIA, A CORPORATION OF DELAWARE

MOTOR CAR TRUCK

Application filed December 12, 1928. Serial No. 325,444.

The invention relates to means for supporting the motor frames or casings in motor car trucks and more particularly to the type in which the frame or casing of an electric motor is swiveled at one end to the wheel axle to which the motor is geared, and has a projecting nose at its opposite end that engages supporting means on a part of the car truck frame.

With the means at present in use for mounting such motors, it is difficult and expensive to remove the motors from the trucks for repairs, replacements and the like, and it is usually necessary to remove the wheels, axles and journal boxes with the motor. Also, in some cases, the brake rigging must be disconnected.

The present invention seeks to provide improved, simplified supporting means for the motor nose which will hold the motor casing against substantial vertical movement in opposite directions from its normal position and which can be readily adjusted to permit the vertical swinging movement of the motor either up or down and thus permit access to the motor or its removal without disassembling other parts.

The invention consists in the features of improvement hereinafter set forth, illustrated in the preferred form in the accompanying drawings and more particularly pointed out in the appended claims:

In the drawings:

Fig. 1 is a view partially in elevation and partially in longitudinal section of a motor car truck, to which is applied the present improved supporting means for the motor casing.

Fig. 2 is a plan view and Fig. 3 an elevation of the supporting means, parts being shown in section in Fig. 3 on the lines 3—3 of Figs. 1 and 2.

Fig. 4 is a detail section on the line 4—4 of Fig. 3.

The present improvement is applicable to car trucks of different construction. That shown in the drawings comprises cast metal side frames 1 integrally connected by central transverse members 2 that form the truck transom and which are spaced apart

to receive the spring plank 3, bolster springs 4 and bolster 5, the spring plank being supported, as usual, from the transom members 2 by hangers 6 and cross bars 7. The truck side frames are provided with the usual pedestals 8 for the journal boxes 9 and are supported by equalizer springs and bars 11 and 12 which are carried in turn by the journal boxes.

An electric motor is mounted on and geared to one of the wheel axles 13 and, if desired, each axle may be provided with a motor. As shown, the motor frame or casing 14 is swiveled at one end on the wheel axle and is removably connected thereto by a suitable axle cap 15. At its opposite end, the motor frame is provided with a nose which, in the form shown, comprises upper and lower centrally disposed jaw lugs 16 which engage and hold between them a transversely disposed supporting unit comprising upper and lower spring bars 17 and 18 and an interposed semi-elliptical spring 19.

The improved supporting means, in the preferred form shown, is divided and comprises upper and lower pairs of supporting arms 20 and 21 which are carried on the adjacent face of the transom member 2. These arms are mounted in horizontally disposed guideways or seats formed by vertical and horizontal flanges or lugs 22 and 23 which are cast upon the adjacent face of the transom member 2. These lugs or flanges securely support the arms in operative position with the inner ends of the upper pair of arms above the end of the upper spring bar 17, and the inner ends of the lower pair of arms 21 below the ends of the lower spring bar 18, as shown most clearly in full lines in Fig. 3. The arms are held in their operative positions by pairs of bolts 24 and 25 extending vertically through the horizontal flanges 23 and through holes formed in the arms.

By placing the truck over a pit and removing the bolts 25, the lower pair of supporting arms 21 can be moved laterally and outwardly to the position shown in dotted lines in Fig. 3, and the motor swung down-

wardly about the axle and so readily removed. If the truck is taken from under a car, and the upper pins 24 removed, the upper pair of arms 20 can be similarly adjusted laterally and outwardly and the motor swung upwardly about the axle.

Thus, the raising, lowering or removal of the motor for replacements, repairs and the like can be readily effected without dismantling the other parts of the truck. Preferably, the guideways or seats formed by the flanges 22 and 23 are open at their outer sides to facilitate the insertion of the supporting arms. It is also noted that, in the form shown, the motor casing is provided with additional lugs 26 which will rest upon the inner ends of the upper pair of supporting arms in case the spring 19 is weakened or broken. Where, as usual, such additional safety lugs are provided, the upper as well as the lower supporting arms must be moved outwardly to permit the lowering of the motor frame from its normal position. With the construction shown, the weight of the motor and the load due to rotation of the motor in one direction is transmitted by the upper jaw member 16 through the spring unit to the lower movable supporting arms 21, and the load, due to rotation of the motor in the opposite direction, is transmitted by the lower jaw lug through the spring unit to the upper pair of movable arms 20. The adjustable supporting arms 20 and 21 thus form seating members for the ends of the spring assembly or unit. It is also noted that the vertical flanges 22 on the truck transom prevent lateral displacement of the spring unit.

The invention is applicable to different types of trucks and motors and many changes can be made in the details set forth without departure from the scope of the appended claims.

I claim as my invention:

1. In a car truck, the combination with a wheel axle and a transverse truck member, of a driving motor having a frame or casing swiveled on the wheel axle, and interengaging supporting parts carried by and projecting from the adjacent portions of the transverse truck member and the motor frame for holding the latter in position, said supporting parts including a spring unit, safety lugs and certain other parts that are laterally adjustable to permit the unobstructed vertical swinging movement of the motor frame in opposite directions from its normal position, substantially as described.

2. In combination with the wheel axle and transom of a car truck, of a motor frame or casing swiveled on the wheel axle and projecting toward the truck transom, a spring assembly, and cooperating supports projecting from the motor frame and transom and engaging the spring assembly, certain of

said supports being mounted for lateral adjustment to permit the vertical swinging movement of the motor frame, substantially as described.

3. In combination with the wheel axle and transom of a car truck, of a motor frame or casing swiveled at one end on the wheel axle and having a projecting nose and a safety lug on its opposite end, and supports mounted on the adjacent face of the truck transom and cooperating with the nose and safety lug of the motor frame to hold the latter against substantial vertical movement, said supports being secured to the transom and laterally adjustable thereon out of cooperative relation with the motor nose and safety lug to permit the unobstructed vertical swinging movement of the motor frame in opposite directions from its normal position, substantially as described.

4. In combination with the wheel axle and transom of a car truck, of a motor frame or casing swiveled at one end on the wheel axle and having a projecting nose on its opposite end, and divided supporting means carried by the truck transom and comprising separate parts disposed on opposite sides of the motor nose and laterally adjustable to and from the same to prevent or permit the vertical swinging movement of the motor frame, substantially as described.

5. In combination with the wheel axle and transom of a car truck, of a motor frame or casing swiveled at one end on the wheel axle and having a projecting nose on its opposite end, upper and lower pairs of supports carried by the truck transom and guided thereon for lateral adjustment to and from the motor nose to prevent or permit the vertical swinging movement of the motor frame, and bolts for releasably securing the supports in operative position, substantially as described.

6. In combination with the wheel axle and transom of a car truck, of a motor frame or casing swiveled at one end on the wheel axle and having projecting jaw lugs on its opposite end, a spring unit interposed between said jaw lugs, and supports mounted on the adjacent face of the truck transom and laterally adjustable into and out of position above and below said spring unit, substantially as described.

7. In combination with the wheel axle and transom of a car truck, of a motor frame or casing swiveled at one end on the wheel axle and having projecting jaw lugs on its opposite end, a spring and spring bars interposed between said jaw lugs, upper and lower pairs of supports mounted on the truck transom and extending respectively above and below the ends of said spring bars, said supports being guided for lateral adjustment on the transom into and out of operative position and bolts for releasably

securing the supports in operative position, substantially as described.

8. In combination with the wheel axle and transom of a car truck, of a motor frame or casing swiveled at one end on the wheel axle and having projecting jaw lugs on its opposite end, a spring and spring bars interposed between said jaw lugs, guide lugs on the adjacent face of the truck transom, upper and lower pairs of supporting arms adjustably supported by said guide lugs to move into and out of operative position above and below the ends of said spring bars respectively, and bolts extending vertically through the guide lugs and supporting arms for releasably holding the latter in operative position, substantially as described.

9. In a motor car truck, supporting means for the motor nose comprising a spring assembly, and cooperating parts carried by the truck transom and guided thereon for lateral adjustment into and out of operative position relative to the spring assembly to prevent or permit the vertical swinging movement of the motor in opposite directions from its normal position, substantially as described.

10. In a motor car truck, supporting means for the motor nose comprising a spring unit, and seating members for the spring unit carried by the truck transom and guided thereon for lateral adjustment into and out of operative position above and below the ends of the spring unit to permit or prevent the vertical swinging movement in opposite directions of the motor, and bolts for releasably securing said seating members in operative position, substantially as described.

11. In a motor car truck, upper and lower pairs of supporting arms for the motor nose carried by the truck transom and guided for lateral adjustment thereon into and out of operative position, and vertical bolts for releasably holding the supporting arms in operative position, substantially as described.

12. In a car truck, the combination with the wheel axle and a transverse truck member, of a motor frame or casing swivelled at one end on the wheel axle and having projecting jaw lugs at its opposite end adjacent the truck member, a transverse supporting unit interposed between said jaw lugs and cooperating supports mounted on the adjacent face of the truck member and laterally adjustable into and out of position above and below the ends of said supporting unit, substantially as described.

13. In a car truck, the combination with a wheel axle and a transverse truck member, of a motor frame movably mounted on the wheel axle and projecting toward said transverse member, a spring assembly inter-

posed between the adjacent portions of the motor frame and the transverse truck member, and supports on said frame and said member engaging the spring assembly, the supports on one of said parts being adjustable into and out of engagement with the spring assembly to prevent or permit the vertical swinging movement of the motor frame.

14. The combination with the wheel axle and transom of a car truck, of a motor frame swiveled at one end on the wheel axle and projecting toward the truck transom, a transverse spring unit interposed between the adjacent portions of the motor frame and the transom, jaw lugs on one of said parts engaging the spring unit intermediate its ends and seating members mounted on the other of said parts and adjustable thereon into and out of position above and below the ends of the spring unit.

15. In a car truck, the combination with a wheel axle and a transverse truck member, of an interposed motor frame movably mounted on the wheel axle and having a projecting nose adjacent the transverse truck member, a spring assembly engaged by the motor nose and supporting parts mounted on the transverse truck member and adjustable thereon into and out of engagement with the spring assembly to prevent or permit the vertical swinging movement of the motor frame.

16. In a motor car truck, the combination with a wheel axle and truck transom, of an interposed motor frame swiveled on the wheel axle and having a projecting nosing and safety lugs adjacent the truck transom, a spring assembly engaged by the motor nosing and supports for the spring assembly mounted on the adjacent face of the truck transom and normally disposed below said safety lugs, said supports being adjustable out of cooperative relation with the spring assembly and safety lugs to permit the lowering of the motor frame from its normal position.

17. In a motor car truck, the combination with a wheel axle and truck transom, of a motor frame swiveled on the wheel axle and having projecting jaw lugs and safety lugs adjacent the truck transom, a transverse spring unit interposed between said jaw lugs, and supporting parts mounted on the truck transom and disposed above and below the ends of the spring unit and below and spaced from said safety lugs, said supporting parts being laterally adjustable into and out of operative position to prevent or permit the vertical swinging movement of the motor frame in opposite directions from its normal position.
